(57) **CLAIM**

The ornamental design for a combined eyebrow razor and cover, as shown and described.

DESCRIPTION

FIG. 1 is a perspective view of the first component of a combined eyebrow razor and cover embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is a perspective view of the second component of a combined eyebrow razor and cover embodying my new design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is an enlarged top plan view thereof;

FIG. 14 is an enlarged bottom plan view thereof;

FIG. 15 is a perspective view of the combined eyebrow razor and cover with the first and the second components shown together;

FIG. 16 is a front elevation view thereof;

FIG. 17 is a rear elevation view thereof;

FIG. 18 is a left side elevation view thereof;

FIG. 19 is a right side elevation view thereof;

FIG. 20 is an enlarged top plan view thereof;

FIG. 21 is an enlarged bottom plan view thereof;

FIG. 22 is an enlarged view of the selected portion 22 in FIG. 1; and,

FIG. 23 is an enlarged view of the selected portion 23 in FIG. 4.

The broken lines shown in the figures depict portions of the combined eyebrow razor and cover that form no part of the claimed design. The dash-dot broken lines in the figures are demarcating enlarged areas and form no part of the claimed design.
